CLAIM

The ornamental design for a jaw slide, as shown and described.

DESCRIPTION

FIG. 1 is a perspective view of a jaw slide, showing our new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a left side elevational view thereof; and,

FIG. 7 is a right side elevational view thereof.

The broken line showings of a rod and a plug connector in FIG. 1 are for illustrative purposes only and form no part of the claimed design.
